UNITED STATES PATENT OFFICE

JOSEPH LAURENCE, OF CLEVELAND, OHIO

DESIGN FOR A MONEY BANK

Application filed March 19, 1931. Serial No. 39,142. Term of patent 14 years.

To all whom it may concern:

Be it known that I, JOSEPH LAURENCE, a citizen of the United States, residing at Cleveland, in the county of Cuyahoga and State of Ohio, have invented a new, original, and ornamental Design for Money Banks, of which the following is a specification, reference being had to the accompanying drawing, forming part hereof, wherein the figure is a perspective view of a money bank showing my new design, the two sides of the structure being identical with each other.

I claim:

The ornamental design for a money bank as shown and described.

JOSEPH LAURENCE.
